UNITED STATES PATENT OFFICE.

JOHN M. BEECH, OF CINCINNATI, AND LUKE P. BEECH, OF NORWOOD, OHIO.

HYDROCARBON-BURNER.

SPECIFICATION forming part of Letters Patent No. 716,174, dated December 16, 1902.

Application filed February 15, 1902. Serial No. 94,254. (No model.)

To all whom it may concern:

Be it known that we, JOHN M. BEECH, a resident of Cincinnati, and LUKE P. BEECH, a resident of Norwood, in the county of Hamilton and State of Ohio, citizens of the United States of America, have invented certain new and useful Improvements in Hydrocarbon-Burners, of which the following is a specification.

- 10 This invention relates to certain improvements in hydrocarbon-burners such as are especially designed for use in burning fuel-oils; and the object of the invention is, in part, to provide a burner of this character of an improved and simplified construction adapted for substantially perfect combustion of heavy and crude fuel-oils—as crude petroleum, for example—and in part to adapt such a burner for use in a heater.
- 20 The invention consists in certain novel features of the construction, combination, and arrangement of the several parts of the improved burner whereby certain important advantages are attained and the device is rendered simpler and cheaper and is otherwise better adapted and made more convenient for use, all as will be hereinafter fully set forth.
- The novel features of the invention will be carefully defined in the claims.
- 30 In the accompanying drawings, which serve to illustrate the invention, Figure 1 is an axial section taken through a warm-air heater provided with a burner constructed according to our invention, and Fig. 2 is a transverse section taken through the fire-pot of the heater in the plane indicated by the line *a a* in Fig. 1 and showing the burner in position therein. Fig. 3 is a transverse section taken through the heater in the plane indicated by the line *b b* in Fig. 1 and showing certain features of construction to be hereinafter referred to. Fig. 4 is a detail view showing the diaphragm which forms the bottom of the fire-pot of the heater. Fig. 5 is a plan view showing detached the lower part or section of the spreader or deflector. Fig. 6 is an enlarged sectional detail view showing certain details of construction of the overflow device to be hereinafter referred to.
- 50 As shown in the views, the heater is constructed with a cylindrical shell 1, the lower edge of which fits outside of a raised flange

4 on a base-ring 2 and the upper edge of which supports a perforated cap 3, having openings 5 in it for the free upward passage of heated air from within the shell. The base-ring 2 is constructed with a central circular bottom plate or table 6, having a raised edge flange 7 and supported at the rear of the shell by braces 4^a 4^b, extended across the space between the flange 7 and shell 1, said space (indicated at 10 on the drawings) being open for the entry of air from below into the shell to be warmed. The table 6 has a depressed central portion 8, which is extended forwardly 65 across the space 10 at the front of the shell, said shell having at its front a door-plate 13^a, on which are held doors 13 13, by means of which access may be had to the burner within the shell.

70 9 indicates a semicylindrical part formed, by preference, from sheet metal and arranged concentrically within the shell 1, the front portion of said part 9 being open in line with the doors 13, as shown in Figs. 2 and 3, and the lower edge thereof being supported outside of the flange 7 upon an annular flange or ledge upon the table 6. The space 10 is continued up between the shell and part 9, so as to produce an annular air-flue for the 80 upward passage of air to be warmed within the shell.

At the front of the heater and at opposite sides of the doors 13 are erected two similar plates 11 11, the lower ends of which rest upon table 6 and are held against outward movement by spaced lugs or projections 6^a thereon. These plates are similar in form and extend across the space 10 from the table 6 to the top of the part 9, where they are held together by a crown-piece 12, extended between them and secured in place by screws or otherwise. Each plate 11 has a rear flange 11^a produced upon it, and this flange takes outside of one vertical edge portion of the part 9, holding the same securely in place against the flange 7 of table 6, and at the front edge of each such plate 11 is produced another flange 11^b, which takes against the inner face of the shell 1 along one edge of the opening produced in said shell at the door-plate 13^a, so that the edges of said shell at said opening are securely held between said flanges and the door-plate, as shown in Figs. 2 and 3.

At the top of the part 9 is arranged an annular part or ring 15, of L shape in cross-section, on which is supported a top plate 16, which closes the upper part of the space 14, 5 inclosed within said part 9, so that the gases from the combustion of the fuel or the odors from the crude oil may not escape and be mingled with the air being warmed within the air-flue 10 of the shell 1. Another annular part or ring 17, of L shape in cross-section, 10 is extended around the inner wall of the part 9 at the central part thereof, and on this part 17 is supported a diaphragm 18, which is extended across the space 14 within the part 9 15 and forms above it a fire-pot 19, within which the combustion of the fuel is effected. The ring or part 17 is cut away at its front portion opposite the doors 13 to permit the removal of the diaphragm, which is loosely supported on said ring, and the diaphragm has a forward extension 18^a, extended out between the plates 11 and rested at its front edge upon a bridge-piece 13^b upon the door-plate 13^a. The fire-pot 19 thus produced has a smoke-outlet 20, extended across the flue 10, outside the shell 1, and adapted to receive a stove-pipe for connection with a flue in a well-known way.

The diaphragm 18 has a depressed central 30 portion 21, formed with a central opening, through which is extended downwardly, within the space 14 and below the diaphragm, a draft-tube 22, of cylindrical form, provided with closely-adjacent perforations in its walls 35 and formed, by preference, from sheet metal bent into shape and riveted along its edges for the sake of lightness and cheapness. The lower end of this draft-tube is arranged within the open top of a fuel cup or receptacle 24, 40 also of circular form, the interior cavity of which is of greater diameter than the lower end of the draft-tube, so that an annular air-passage is provided around the lower end of the draft-tube for the entry of air for the 45 combustion of the liquid fuel contained within the cup or receptacle. To hold the lower end of the draft-tube central within the cup or receptacle, said end is provided with outward projections 22^a, taking inside the cup 50 or receptacle, as shown in Fig. 3. Fuel is supplied to the cup or receptacle 24 by way of a fuel-supply pipe 25, extended back beneath the rear part of the table 6 and having connection with an overflow device 27, arranged in the air-flue 10. Beyond this overflow device the fuel-supply pipe is extended rearwardly and is bent up outside shell 1 and has connection at its upper end with an elevated supply tank or reservoir 26 for containing 55 a supply of fuel-oil. The construction of the overflow device 27 is shown in detail in Figs. 1 and 6. This device has a downwardly-directed arm or branch provided with a fuel-passage the highest point in the floor of which is above the point of connection of the pipe 25 with said device 27, so that fuel may flow into the cup or receptacle 24 from said pipe

before any may escape by way of said downwardly-directed arm or branch. The said arm has a nipple 28 screwed into its end, and 70 the lower extremity of said nipple is arranged to discharge into a funnel-like part 29 at the inlet of an overflow tank or reservoir 30, arranged beneath the base-ring, as shown in Fig. 1. By this arrangement when the fuel 75 in the cup or receptacle 24 rises above a predetermined level the surplus fuel will escape through the passage of the downwardly-directed arm of the overflow device and will be discharged through the nipple 28 into the overflow tank or reservoir, from which it may be poured back from time to time into the fuel-tank 26, so that waste of the fuel is prevented. 80

The diaphragm 18 is formed with three equidistant openings 31, and above said diaphragm is arranged, within the fire-pot, a hollow or shell-like deflector or spreader 34, having arms 33, formed with hollows or air-passages which receive air from beneath the diaphragm through the said openings 31 and 90 carry it upward into the central hollow of the shell. The upper face of the diaphragm is formed with bosses encircling the openings 31, as seen at 32, and these bosses 32 hold the lower ends of arms 33 against lateral movement on the diaphragm. The deflector or spreader 34 is formed in two halves or sections for convenience in construction, there being an upper half 36 and a lower half 37, the construction of the latter being shown in the detail view Fig. 5. These halves or sections have around their meeting edges overlapping flanges 38 to provide a tight joint between them, and the lower half or section is provided in its bottom and also in the upper parts of 100 the arm portions thereof with perforations 35 for the downward discharge of air from within the deflector upon the flames and hot gases issuing from the upper end of the draft-tube. For holding the deflector or spreader in place 105 upon the diaphragm, with the hollows of its arms communicating with the openings 31 in the diaphragm, we provide the upper half or section 36 with lugs 39 on the lower ends of its arm portions, screws or bolts 40 being 110 passed through these lugs and through the diaphragm in a well-known way. By means of its hollow arms 33 the deflector or spreader is supported above the open upper end of the draft-tube, so that the hot gases issuing from 120 said draft-tube will be in the path of the jets of air discharged from the perforations 35. 115

In the operation of the device when fuel is supplied to the cup or receptacle 24 and lighted air for its combustion is drawn in through the 125 annular passage beneath the lower end of the draft-tube, the flames and hot gases being carried up through said tube and discharged from the upper end thereof into the fire-pot 19. To keep the draft-tube from being burned 130 out too quickly, it is kept cooled by the air drawn in through the perforations 23, and such air is mixed with the flames and hot gases within the tube to promote combustion 135

thereof. Upon issuing from the upper end of the draft-tube the flames and hot gases are acted upon by the jets of air discharged at the perforations 35 in the spreader or deflector and are caused to be spread out within the fire-pot 19, so that the walls thereof become highly heated in order to permit of heating the air flowing up through the air-flue 10 inside the shell 1 of the device. In this way also complete combustion of the fuel within the fire-pot is effected, so that there is very little or no deposition of soot, and consequently the passages are not liable to become choked or clogged and do not require constant cleaning, as in the case of various other oil-burners. The odors from the crude fuel-oil are also carried up within the fire-pot, so that they are not permitted to escape into the flue 10. The overflow device is also of a construction to automatically draw off all surplus fuel supplied by pipe 25 after the fuel in the cup or receptacle 24 has reached its predetermined level, so that accidents resulting from overflowing of said cup or receptacle or extinguishing of the flame thereat are altogether avoided and the operation of the improved burner is made entirely safe and easy.

From the above description of our improvements it will be seen that the improved burner is of an extremely simple and inexpensive nature and is especially well adapted for use in heaters, although not at all limited in its use to such devices, and it will also be obvious from the above description that the device is capable of some modification without material departure from the principles and spirit of the invention, and for this reason we do not wish to be understood as limiting ourselves to the exact construction and arrangement of the several parts of the device herein set forth.

Having thus described our invention, what we claim, and desire to secure by Letters Patent, is—

45 1. In a heater, the combination of two parts, one within and of less diameter than the other, whereby an air-flue is formed between said two parts for the circulation of air to be warmed, a diaphragm extended across the space inside the innermost part and forming a fire-pot above it, said diaphragm having a central opening, a burner below the diaphragm and provided with means for discharging products of combustion through the opening in the diaphragm into the fire-pot above the diaphragm and means within the fire-pot and adapted to discharge air against the products of combustion entering said fire-pot through the opening in the diaphragm to spread and diffuse such products of combustion through the fire-pot, substantially as set forth.

2. In a heater, the combination of two parts, one within and of less diameter than the other, whereby an air-flue is formed between said two parts for the circulation of air to be warmed, a diaphragm extended across the space inside the innermost part and forming

a fire-pot above it said diaphragm having a central opening, a cup or receptacle below the diaphragm and provided with means for supplying fuel thereto, a draft-tube having its lower end arranged to receive products of combustion from said cup or receptacle and having its upper end adapted for communication with the central opening of the diaphragm arranged to discharge such products of combustion into the fire-pot above said diaphragm and means within the fire-pot and adapted to discharge air against the products of combustion issuing from the upper end of the draft-tube to spread and diffuse such products of combustion through the fire-pot, substantially as set forth.

3. In a hydrocarbon-burner, the combination of a fire-pot, a diaphragm extended across the bottom of the fire-pot and provided with an opening, a cup or receptacle arranged below the diaphragm and provided with means for supplying fuel thereto, a draft-tube having its lower end arranged to receive flames and gases from said cup or receptacle and having its upper end arranged to discharge into the fire-pot and a spreader in the fire-pot consisting of a hollow shell arranged above the mouth of the draft-tube and formed with a hollow arm adapted for communication with the opening in the diaphragm to receive air from beneath the same, said shell having perforations for the discharge of the air thus received downwardly upon the flames and gases issuing from the upper end of the draft-tube, substantially as set forth.

4. In a hydrocarbon-burner, the combination of a fire-pot, a diaphragm extended across the bottom of the fire-pot and provided with an opening, a cup or receptacle arranged below the diaphragm and provided with means for supplying fuel thereto, a draft-tube having its lower end arranged to receive flames and hot gases from the cup or receptacle and having its upper end arranged to discharge into the fire-pot, and a spreader in the fire-pot consisting of a hollow shell arranged above the mouth of the draft-tube and formed with a hollow arm adapted for communication with the opening in the diaphragm to receive air from beneath the same, said shell having perforations for the discharge of air thus received downwardly upon the flames and gases issuing from the upper end of the draft-tube and being formed in two sections having at their edges overlapping flanges to provide a tight joint between them, substantially as set forth.

5. In a hydrocarbon-burner, the combination of a fire-pot, a diaphragm extended across the bottom of the fire-pot and provided with openings, a cup or receptacle below the diaphragm and having means for supplying fuel thereto, a draft-tube the lower end of which is adapted to receive flames and gases from the cup or receptacle and the upper end of which discharges into the fire-pot and a spreader in the fire-pot consisting of a hollow shell arranged above the mouth of the draft-

tube and formed with hollow arms adapted for communication with the openings in the diaphragm to receive air from beneath the same, said shell having perforations for the discharge of air thus received downwardly upon the flames and gases issuing from the upper end of the draft-tube and being formed in upper and lower halves, and screws for holding the arm portions of the upper half to the diaphragm, substantially as set forth.

6. In a heater, the combination of a part having at its front a door-plate provided with a bridge-piece and having doors at the upper and lower portions of said door-plate, said part also having a smoke-outlet and having a flanged ring extended around its inner wall, a diaphragm rested on said ring and forming

a fire-pot above it and having an extended front portion the front edge of which is rested on the bridge-piece of the door-plate, a cup or receptacle below the diaphragm and having means to supply fuel thereto and a draft-tube the lower end of which is arranged to receive flames and gases from the cup or receptacle and the upper end of which is arranged to discharge into the fire-pot, substantially as set forth.

Signed at Cincinnati, Ohio, this 6th day of February, 1902.
